UNITED STATES PATENT OFFICE.

GUSTAVE A. SCHLECHTER, OF READING, PENNSYLVANIA.

DESIGN FOR A SPOON, &c.

SPECIFICATION forming part of Design No. 21,229, dated December 8, 1891.

Application filed September 16, 1891. Serial No. 405,917. Term of patent 3½ years.

To all whom it may concern:

Be it known that I, GUSTAVE A. SCHLECHTER, a citizen of the United States, residing at Reading, in the county of Berks and State of Pennsylvania, have invented and produced a new and original Design for Spoons or Forks, of which the following is a specification, reference being had to the accompanying drawing, forming a part thereof.

10 The figure is a plan view of the design for a spoon, this view illustrating my design.

The invention relates to the ornamentation of the handles and bowls of spoons or the handles of forks; and the object is to provide 15 an ornamental and æsthetic pattern for the ornamenting of such articles which will give them a unique, characteristic, and historic appearance.

The leading feature of my design resides in 20 the representation of an architectural structure upon the bowl of the spoon, with a series of letters or characters arranged above, producing an ornamental and cloud effect. The

shank of the spoon is also ornamented with a representation of a series of characters so 25 associated as to produce a chain-like effect. Upon the broad portion of the handle of the spoon is the representation of a tower, and at the end of the handle is the representation of a keystone and a number of characters arranged to produce an ornamental and artistic 30 effect about it; but such letters or characters form no part of the invention herein.

There is also upon the handle, at the base of the tower, a representation of a railway-car. 35

In the drawing, the letter A indicates the keystone; B B B, the ornamentation; C, the tower; D, the architectural design on the bowl.

What I claim is—

The design for a spoon, as herein shown 40 and described.

GUSTAVE A. SCHLECHTER.
